[57] CLAIM

The ornamental design for a fragrance bottle, as shown and described.

DESCRIPTION

FIG. 1 is a front elevational view of a fragrance bottle, showing my new design, the rear being a mirror image thereof, the left and right sides being identical to the front, and shown with a moveable protective cap in a protruded position and a moveable bottom element shown in a resulting position recessed into the gridded interior structure; FIG. 2 is a top plan view thereof; FIG. 3 is a bottom plan view thereof; FIG. 4 is a top, front perspective view thereof at an angle of elevation of approximately 45°; FIG. 5 is a top, front perspective view thereof at an angle of elevation of approximately 30°; FIG. 6 is a top, front, perspective view thereof at an angle of elevation of approximately 15°, shown with a movable protective cap partially recessed into the gridded interior structure and a movable bottom element shown in a resulting protruded position;

FIG. 7 is a top, front perspective view thereof at an angle of elevation of approximately 5°, FIG. 8 is a bottom, front perspective view of FIG. 6 at an angle of depression of approximately 15°, FIG. 9 is a bottom, front perspective view thereof at an angle of depression of approximately 30°; and,

FIG. 10 is a bottom, front perspective view of FIG. 6 at an angle of depression of approximately 45°, The change in appearance of the internal gridded structure in FIGS. 4-10 is not due to different positions of the internal structure but is the result of light refracting through the outer spherical structure that creates different appearances at the different angles described in the Figure descriptions.
